UNITED STATES PATENT OFFICE.

ALLAN E. LARD, OF WASHINGTON, DISTRICT OF COLUMBIA, ASSIGNOR TO THE METALLIC SHAFT COMPANY, OF WILMINGTON, DELAWARE, A CORPORATION OF DELAWARE.

GOLF-CLUB.

1,232,816.

Specification of Letters Patent. Patented July 10, 1917.

Application filed October 16, 1914. Serial No. 866,887.

To all whom it may concern:

Be it known that I, ALLAN E. LARD, a citizen of the United States, residing at Washington, in the District of Columbia, have invented certain new and useful Improvements in Golf-Clubs, of which the following is a specification.

My present invention pertains to improvements in golf clubs, and more particularly 10 the shaft employed in connection therewith.

The main object of the invention is to produce a metallic shaft embodying all the desirable and requisite features of a wooden shaft, and eliminating the objectionable features inherent thereto, namely, breaking, warping, becoming "dead" or "set," and the care and attention necessary during and after exposure to rain.

A golf-club shaft must, as is well understood by those skilled in the use of golf-clubs, have proper weight, and also proper balance, and the shaft must have the right "whip" to be effective, the whip being a matter of degree, varying with the taste and requirements of different players.

Satisfactory metallic golf shafts have not, so far as I have been able to ascertain, as yet appeared, and the main difficulty has been the inability to secure the absolutely 30 essential feature of torsion in the shaft. An ordinary hollow steel golf shaft has no torsioning qualities under impact, and such torsioning or twisting of the shaft is just as indispensable in a metallic shaft as it is in 35 a wooden one.

The face of the head of a golf shaft is offset or out of line with the shaft, and consequently when impact against the ball occurs a wooden shaft not only flexes backwardly, but also twists or torsions, and it is such torsioning that adds propelling power which assists in lengthening the drive. Furthermore, this torsioning, co-operating with the turning of the wrists (it being a 45 well-known fact that the wrists must turn in every properly executed golf swing where distance is required), and a proper swing of the club, tends to give a long straight ball with a minimum effort. In short, a 50 longer and a straighter ball can be obtained by a skilled player with a club having a live wooden shaft that torsions than with one which does not.

Another important feature of the torsioning is that it tends to cushion the blow, the

result being a yielding, pleasant sensation rather than a sudden or jarring one. When the head of the club, traveling at a high rate of speed, impacts against the ball, the tendency is to turn the shaft in the 60 hands, and it will be readily seen that the shaft is less liable to jar when this sudden twisting effect is cushioned by the torsioning action of the shaft, such action traveling the length of the shaft and being, to a 65 certain extent, more gradually and pliantly applied to the gripping hands. It is, therefore, quite apparent and a well-known fact to those versed in the science of the game, that torsion is indispensable in a wooden 70 golf-shaft, and it naturally follows that it is just as indispensable in a steel golf-shaft.

Two embodiments of my invention are shown in the annexed drawings, wherein:

Figure 1 is a sectional elevation of a 75 golf club showing my improved shaft applied thereto;

Figs. 2 and 3 transverse sectional views, on a somewhat enlarged scale, taken, respectively, on lines 2—2 and 3—3 of Fig. 1; 80

Fig. 4 is a side elevation of a modified form of shaft; and

Fig. 5 a plan view of the blank from which the shaft may be produced.

Referring to the construction shown in 85 Figs. 1 to 3 inclusive, and which I may here state has been actually produced and tested out, 1 denotes the shaft, which in the present instance is formed of a tapered tube, preferably made of tempered spring steel, to 90 the lower smaller end of which is secured a head 2, while at the opposite end it is provided with the ordinary grip or handle 3. This grip may be produced in any suitable manner. In order to facilitate the attachment of the usual grip to the shaft by tacks, which are now commonly employed, I provide two plugs 4 and 5, the former preferably fluted longitudinally and driven to place within the tube, while the latter is 100 driven into the upper or outer end of the tube. Tacks employed to secure the list- 95 ing and the calf grip, will be driven through the slots and into the plugs.

The shaft 1, as will be noted, is provided 105 with a series of longitudinally-extending slots or slits 6, said slots extending lengthwise of the shaft in four different lines, two of such longitudinally-extending series standing opposite each other and bearing a 110

staggered relation to the other two longitudinally-extending lines of slots. There is thus produced what may be termed a series of longitudinally-extending ribs or members 5 which are curved upon the arc of a circle the center of which is coincident with the axis of the shaft. As shown, the slots 6 extend substantially to the upper end of the shaft and beneath the grip portion of the 10 club, so as to effect, as nearly as possible, the torsioning action which obtains in a wooden shaft under impact. It is, of course, conceivable that the slots or openings may not be arranged in the exact relation shown in 15 Fig. 1, so long as there be a plurality of slots or openings which will permit the shaft to torsion and yet render it sufficiently strong to prevent it from buckling when in use. The arrangement of the slots or openings 20 quartering around the tube and one series of slots bearing a staggered relation to the next adjacent series, has been found quite efficient, and produces in the shaft that degree of torsion which is present in a high-grade wooden shaft, an article which it is 25 becoming more and more difficult to obtain. In fact, it is not now possible, owing to the scarcity of suitable wood, to obtain shafts in sufficient number to anywhere nearly fill the 30 demand therefor.

The manner in which the tube is formed is immaterial. Tapered steel tubing is readily drawn or swaged, and such tube may be slotted and tempered, or the tube may be 35 formed up from a blank in which the slots or openings are initially produced, as in Fig. 5.

Moreover, the shaft need not be tapered, for, as shown in Fig. 4, it may be produced 40 from a truly cylindrical tube or brought into the desired tubular form from a blank, the diameter of the finished article being the same throughout. Slots or openings in this form are shown the same as in the other, 45 though, as will be understood, the invention is not limited to the specific arrangement of slots or openings disclosed.

Under both constructions the shaft may be said to have a series of curved or arc-shaped members extending longitudinally 50 thereof and connected together by ears or members 7. The degree of torsion will, of course, be dependent upon the number of the slots and the size thereof.

55 The whip, under the construction illustrated in Fig. 1, may be located or accentuated at any desired point in the length of the shaft by varying the diameter thereof at the point where the whip is to be produced. Thus, it may be localized adjacent the head, near the grip, or in the middle of the shaft. The size of the slots also has a bearing on the whip.

As will be readily appreciated, the shaft 65 may be treated or enameled to prevent rust,

and when made of high-grade steel and properly tempered its life is almost limitless.

Any suitable light filling material may be inserted in the tube, as for instance, cotton, cork or wicking, in order to deaden the metallic ring which would otherwise be present when the head of the club impacts with the ball. 70

If desired, the shaft may be wrapped to cover the slots, and to prevent ingress of 75 moisture to the interior of the shaft where, if it be not protected by enameling or otherwise, rust might ensue. Such wrapping moreover may be employed to strengthen 80 the shaft, if perchance this strengthening should be found necessary, though in practical use it is apparently not needed.

The head 2 may be secured to the shaft in any desired manner, as by the employment of a screw 8, passed through the lower 85 end of the shaft and into the head, see Fig. 1, which is additional to the driving fit which is secured with a tapered shaft, and the presence of any cementitious material which may be placed in the socket in the 90 head. A through-pin 9 may likewise be employed, though this will probably be found unnecessary.

As shown in Fig. 4, a bushing 10 may be placed in a socket in the head, and the tube 95 driven into such bushing. This may be necessary where the heads are bored out to receive a wooden shaft which may be of a diameter larger than the metallic shaft to be inserted. Any form of bushing may be 100 employed, but preferably a wooden one will be used in conjunction with a wooden head. Where the shaft is applied to a metallic head, a metallic bushing will be employed, if necessary, and the parts brazed or soldered together, with the shaft in place in the bushing; but where the bushing is not essential or necessary the shaft will be directly secured in the socket formed in the 105 head. 110

Having thus described my invention, what I claim is:

1. As a new article of manufacture, a metallic golf-shaft, substantially cylindrical in cross-section, composed of a series of 115 curved and interconnected body members extending longitudinally thereof.

2. As a new article of manufacture, a metallic golf-shaft, substantially cylindrical in cross-section, composed of a plurality 120 of body members extending longitudinally of the shaft and curved in cross-section, said members tapering toward the lower end of the shaft and being interconnected.

3. As a new article of manufacture, a 125 tubular metallic golf shaft, substantially cylindrical in cross-section, produced from a sheet of metal brought into form, with a plurality of body members extending longitudinally of the shaft and connected to each 130

other by a plurality of ears at spaced intervals throughout the length of the shaft.

4. As a new article of manufacture, a tubular metallic golf shaft, substantially 5 cylindrical in cross-section, formed from a single sheet of metal and having a plurality of tapered body members extending lengthwise thereof, said members being connected at spaced intervals throughout their length 10 by ears.

5. As a new article of manufacture, a tubular metallic golf shaft, cylindrical in cross-section, provided with a plurality of series of longitudinally-extending slots, the 15 slots of one series bearing a staggered relation to those of the others.

6. As a new article of manufacture, a tubular metallic golf shaft, cylindrical in cross-section, said shaft being provided with 20 a plurality of series of longitudinally-extending slots, the slots of one series bearing a staggered relation to those of the next adjacent series upon each side thereof.

7. In a golf club, the combination of a

hollow metallic shaft; a head secured thereto; a plug mounted in the shaft adjacent the lower end of the grip; a second plug secured in the upper end of the shaft; and a grip overlying the shaft and secured to said plugs. 25

8. In a golf club, the combination of a hollow slotted metallic shaft; a head secured thereto; a plug mounted in the shaft adjacent the lower end of the grip; a second plug secured in the upper end of the shaft; 30 and a grip overlying the shaft and secured to said plugs. 35

9. A golf club comprising a tubular shaft substantially cylindrical in cross-section and formed with a plurality of slits therein 40 arranged in staggered relation.

In testimony whereof I have signed my name to this specification in the presence of two subscribing witnesses.
